MEANS FOR INTRODUCING FLAVOR IMPARTING AGENTS INTO TOBACCO AND TOBACCO ARTICLES

Walter T. Canan, 2518 E. Huntington Drive,
Duarte, Calif.

Filed Aug. 22, 1960, Ser. No. 50,967
2 Claims. (Cl. 131—133)

This invention relates to new and useful means whereby volatile aromatic flavor imparting agents may be introduced into tobacco and tobacco articles.

This application is a continuation-in-part of an application Serial No. 862,100 filed by applicant December 28, 1959 now Patent No. 3,026,881 issued March 27, 1962.

Hitherto, various flavoring agents have been introduced into smoking tobacco and tobacco articles as a step in tobacco manufacturing processes. Also it has been proposed to introduce certain volatile flavoring agents into manufactured smoking articles, the expedient of storing same in a confined space together with the flavoring agents, over a period of time, whereby the characteristics of the volatile substances are transferred to the tobacco. However, by whatever means introduced, the flavored tobacco or tobacco article is usually available to the consumer as a finished article, the smoker having no control over the process or the amount of flavoring agent.

The present invention constitutes a departure from prior practice in that there is herewith made available a means whereby the smoker himself may introduce the flavor of his choice in the amount he selects in a convenient, simple and practical manner.

In accordance with the present invention the smoker is enabled to introduce a flavor modifying agent, manually and immediately prior to consuming the tobacco.

An object of the present invention accordingly consists in the provision of means for manually and selectively introducing into a tobacco article flavor modifying agents according to the taste and preferences of the smoker.

A further object of the invention consists in the provision of an applicator for applying menthol or a menthol containing composition to tobacco articles wherein the menthol composition associated with the applicator will remain stable and at full strength for a long period of time preceding use.

Recently, menthol has greatly increased in favor as an addition to smoking tobacco. The effect of the menthol is to impart to the smoke derived from burning tobacco a characteristic liked by many smokers. The terms usually applied to describe this characteristic are "coolness," "flavor," "aroma," and the like. None of the terms in current use are precisely descriptive of the specific menthol characteristic, nor in fact can it be said that the effect of menthol is fully understood. It may well be that the chief effect of menthol is a certain anti-irritant effect. However, so far as menthol preference is concerned, the main point is that the smoker personally finds the mentholated tobacco more agreeable than non-mentholated tobacco. In this application the menthol sensation will be referred to simply as "flavor" and menthol as a "flavoring agent," it being understood that these terms comprehend the alteration in the characteristics of the tobacco smoke with which this invention is concerned.

Moreover it is common practice to incorporate with menthol certain other flavoring agents such as essential oils, mint and the like, and in this view it is contemplated that the menthol prepared in accordance with this invention may contain added flavoring agents useful in the conditioning and "aromatizing" of tobacco. Also it is within the scope of this invention to incorporate with menthol certain substances for the purpose of modifying the physical characteristics of menthol. For this latter purpose

2

many materials are available, a characteristic of which consists in the avoidance of introduction of objectionable flavor. Among such substances may be mentioned ethyl alcohol, ether, glycerine, ethylene glycol, inert or non-combustible filling or thickening agents.

It being an object of the invention to impart a flavor that is essentially recognizable as the menthol flavor, which although it may be attained by the employment of a composition containing a major proportion of menthol, also may be attained when the menthol is in minor amount, as for example when the menthol is in the form of a composition having ethyl alcohol in preponderant amount, the term "composition consisting essentially of menthol" is herein employed to denote any composition containing menthol wherein the menthol flavor is readily apparent to the smoker.

Whereas, as described in my prior application, Serial No. 862,100, above referred to, the basic objects of the invention therein described may be attained by means of a simple applicator comprising a shank of wood or other suitable material bearing at one end a head formed from a substantially solid menthol composition, which may be provided with a cover, I have found that due to the low vapor pressure of the volatile materials it is desirable to make further provision for preventing escape of the composition.

While the means described in my prior application has proved quite satisfactory under ordinary atmospheric conditions, these conditions are not always maintained. For example, in a building, or in a vehicle, during summer heat the temperature may rise to and above the melting point of the menthol composition. If the menthol composition remains liquified, for any considerable period of time, the composition will flow and escape. Accordingly it is a further object of the present invention to provide special means for preventing the effect of liquefaction when the menthol composition is put up in the form of an applicator.

In accordance with the present invention, the escape of liquified menthol composition may be avoided by encasing the menthol composition in a sealed container or preferably by so forming the head of the applicator that the menthol composition is preferentially retained therein by surface tension.

The features of novelty of the present invention are pointed out with particularity in the claims annexed to and made a part of this specification. However in order that the invention may be fully understood and readily practiced, certain specific embodiments thereof will be described reference being had to the accompanying drawings.

FIG. 1 illustrates an applicator provided with means for avoiding escape of liquified menthol composition according to the present invention.

FIG. 2 is a section taken on the line 2—2 of FIG. 1.

FIG. 3 illustrates an applicator of the type shown in FIG. 1 having a modified head construction.

FIG. 4 illustrates a further modification of head construction in an applicator of the type shown in FIG. 1.

FIG. 5 is an end view of the head of the applicator shown in FIG. 3.

FIG. 6 is an end view of the head of the applicator shown in FIG. 4.

FIG. 7 illustrates a second type of applicator provided with means for avoiding escape of liquified menthol composition according to the present invention.

FIG. 8 illustrates the insert provided with the applicator illustrated in FIG. 7.

FIG. 9 illustrates a third type of applicator provided with means for avoiding escape of liquified menthol composition according to the present invention.

FIG. 10 illustrates the method of applying menthol

composition to a cigarette, according to the present invention.

As shown in FIGS. 1 to 6, the applicator 12 constructed in accordance with the present invention consists of a wire shank 14 and a wire head portion. The wire shank 14 consists of a plurality of thin wires twisted or interwoven and has sufficient rigidity to facilitate grasping in the manner shown in FIG. 10. In FIG. 1 the shank 14 consists of four thin wires which extend and continue to form the head portion 16. The latter consists of four small loops or eyes 18. The head portion 16 is encased in a cover 20 which is composed of a thin impervious material, and the cover is secured by means of a collar 22. The wire loops 18 as may be clearly seen in FIGS. 1 and 2 form a retainer or cage wherein the menthol composition 24 may be retained or trapped.

In FIGS. 3 and 5, the shank portion 14 is formed of two wires twisted or interwoven to provide rigidity, and extended to the head portion 16a, and there formed into two loops 18a located successively in the direction of the axis of the applicator and disposed axially substantially at right angles to each other. A cover 20a similar to cover 20 may be placed over the head portion and secured by a strip or collar similar to element 22 of FIG. 1, and the loops 18, prior to affixing the cover, are filled with a menthol composition. It will be understood that the spacing of the covers 20, 20a and 20b outward from the loops 18, 18a and 18b, is somewhat exaggerated for purposes of illustration. Retaining strip 22 may be provided with adhesive for sealing purposes and with an extension whereby the end of the strip may be grasped and stripped off in manner known to the art.

In FIG. 4, a shank portion 14 composed of two wires is shown. Otherwise stated, a single thin wire of somewhat greater length than twice the length of the completed applicator is looped at 18b and twisted together for the remainder of its length to form the shank portion 14.

The operation of the applicators shown in FIGS. 1 to 6 is as follows: the vaporization of the menthol composition 24 normally is prevented by the covering elements 20, 20a, and 20b. However, should the ambient temperature reach or rise above the melting point of the menthol composition, retention of the menthol composition is adversely affected by escape of the liquid which is able to penetrate under the cover at the zone of the collar 22. Further upon resolidification the menthol composition tends to adhere to the interior of the covers 20, 20a and 20b, whereby when the cover is removed the menthol composition is removed also, unless some special provision is made. In accordance with the present invention, however, the wire loops are able to hold a substantial portion of the menthol composition by virtue of the surface tension and capillary characteristics of the liquid and thus prevent its escape. The arrangement according to the present invention thus affords a very considerable advantage inasmuch as the temperature of liquification of a menthol composition frequently is reached under ordinary conditions as in storage in buildings, in transportation vehicles, and elsewhere.

In FIGS. 7 and 8 the menthol composition is preserved in a tube 26, which is formed of a soft flexible metal or plastic, and wherefrom the composition may be extruded by simply removing the cap 28 and squeezing the tube. However, in this arrangement it is preferred to incorporate an insert 32 formed of corrugated wire. The functions of the latter are several. The enlarged or head portion 36 serves to assist in sealing in the composition 30. The operative portion 34 serves as a means to stir and

distribute the composition to prevent clogging, inasmuch as it is an object to employ only a very small portion of composition and to keep down the diameter of the tube to a minimum. The insert 32 further serves to stiffen and keep open the tube which being quite small will easily be bent or otherwise distorted. The insert 32 further serves as an applicator in its own right whereby portions of the contents of the tube can be removed and applied to the tobacco article.

The further modification shown in FIG. 9 is formed from a shank portion 52 bearing at one or preferably at each end sealed ampoules 44 and 46 filled with unit dosages 40 and 42 of menthol composition. In this illustration the shank 52 and the ampoules 44 and 46 are formed of one substantially continuous piece of glass. The ampoules 44 and 46 are formed with thin walls. In using this applicator the tip 48 of ampule 46 may be seized and broken to release the contents 42 of the ampule. To facilitate breakage the ampule is scored at break-off line 54. After exhausting the contents by applying the contents of the ampule to a tobacco article in the manner shown in FIG. 10, the other ampoule 44 which is still intact may be similarly employed by breaking off tip 50 to release contents 40.

Whereas the type of applicator shown in FIGS. 1 to 6 is primarily designed for normally solid menthol compositions, the forms illustrated in FIGS. 7 to 9 are particularly desirable when pasty or normally liquid menthol compositions are used.

Having now described and illustrated preferred forms of applicators according to the present invention, what I particularly desire to claim is as follows:

1. A menthol applicator for manually applying localized coating of menthol composition to manufactured tobacco articles, comprising a head and a shank, the latter being formed of twisted filamentary material, said head being composed essentially of menthol composition, said head being provided with at least one loop of filamentary material connected to said shank, the opening in said loop being of sufficiently small dimensions to retain said menthol composition by surface tension when said composition is liquified, said menthol composition being of sufficiently small amount to effect retention thereof by said loop, substantially in entirety when said composition is liquified.

2. A menthol applicator for manually applying localized coating of menthol composition to manufactured tobacco articles, comprising a head and a shank, said head containing a composition consisting essentially of menthol, said head being provided with a filamentary loop forming an opening of sufficiently small dimensions to retain said menthol composition by surface tension when said composition is liquified, said menthol composition being of sufficiently small amount to effect retention thereof by said loop, substantially in entirety when said composition is liquified.
